UNITED STATES PATENT OFFICE

ERWIN E. MILLER, OF FULLERTON, CALIFORNIA

EXPANSIBLE PISTON

Application filed May 10, 1926. Serial No. 107,994.

This invention relates to improvements in pumps, and particularly to pistons having expandable packings used therein. The invention may be considered as an improvement over that disclosed in the United States patent issued to William F. McMahon, No. 1,474,201, dated November 13, 1923.

An object of this invention is to provide an improved plunger of novel construction and employing a novel means and method for expanding the packing.

Another object of this invention is to provide an improved plunger or piston which is so constructed that leakage between the heads is effectively prevented.

A further object of this invention is to provide a packing of novel construction primarily designed to facilitate the assembling of parts forming the improved plunger.

20 A still further object of this invention is to provide an improved plunger which may be quickly adjusted and which can be very easily and cheaply constructed.

With the foregoing and other objects in view which will be made manifest in the following detailed description and specifically pointed out in the appended claims, reference is had to the accompanying drawings for an illustrative embodiment of the invention, 30 wherein:

Figure 1 is a section view illustrating the improved plunger as disposed within its cylinder or barrel.

Fig. 2 is a vertical section taken on the line 35 2-2 of Fig. 1.

Fig. 3 is a side elevation of the forward head or the head which is mounted on the sleeve,

Fig. 4 is a front elevation of the same,

40 Fig. 5 is a side elevation of the rear head,

Fig. 6 is a rear elevation of the same,

Fig. 7 is a vertical section through the improved packing, and

Fig. 8 is a side elevation of the packing.

45 Referring to the accompanying drawings wherein similar reference characters designate similar parts throughout, the cylinder or barrel of the pump is indicated at 10, and the plunger rod coupling or cross head which actuates the plunger is indicated at 11. The

improved plunger consists of a plunger rod 12 having one end threaded as indicated at 13 into the plunger rod coupling 11, so that the plunger rod is rigidly secured to the coupling and held against rotation relatively 55 thereto. About the plunger rod 12 there is disposed a sleeve 14, which abuts against the coupling 11 and is provided with a jam nut 15 which can be tightened against the coupling 11. The opposite end of the sleeve 14 is threaded to receive a head 16, this head being clearly shown in Figs. 3 and 4. The head is rigidly secured to the sleeve 14 and has a plurality of projections or fingers 17 formed thereon, which fit between and interlock with similar projections or fingers 18 formed on a second head 19. The end of the plunger rod 12 remote from the coupling 11 is threaded, as indicated at 20, and is reduced to form a pin 21.

70 A threaded sleeve 22 is screwed onto this end of the plunger rod 12 and is tightened in place. It is preferably locked from loosening by means of a cotter pin or the like which can be driven through the aperture 75 23, the cotter pin fitting in grooves or recesses in the ends of the sleeve, which end is preferably hexagonal in form to facilitate the application of a wrench to tighten it onto the plunger rod 12. The head 19 has a closed 80 hub which encloses the end of the sleeve 22. The threads formed on the exterior surface of the sleeve 22 are preferably coarse threads of a relatively steep pitch, and the end of the sleeve which is most adjacent the head 16 is beveled off, forming a beveled shoulder constituting an abutment against which portions of the head 16 and the end of the sleeve 14 may abut on tightening the jam nut 15 against the coupling 11. The two heads 16 and 19 present faces toward each other frusto-conical in form, and between these faces there is disposed an expandable packing 25, which may be formed of an annular ring of rubber so as to be expanded on drawing the heads toward each other. On the inside surface of this packing there are arranged projections 26 which are in staggered relation and which correspond to the openings between the fingers or projections 17 on the 95 100

head 16 and the openings between the fingers or projections 18 on the head 19. The purpose of this construction will be subsequently described.

5 To adjust the plunger or to expand the packing 25 the jam nut 15 is loosened, and a pipe wrench or the like is applied to the sleeve 14, causing this sleeve to rotate. On rotating this sleeve, the two heads 16 and 19 will be rotated together with it, because of the fact that the interlocking or interfitting projections 17 and 18 prevent relative rotational movement between the heads. Consequently, as the head 19 is rotated, it screws up on the sleeve 22, moving toward the head 16 with the fingers 18 merely sliding between the fingers 17. Consequently, the two heads will be forced toward each other and the packing 25 will be forced outwardly. After 20 the adjustment has been made, the jam nut 15 is tightened against the coupling 11, forcing the head 16 and the end of the sleeve 14 into engagement with the beveled end of the sleeve 22.

25 The advantages of this construction are as follows: When the piston is working under ordinary conditions, there is no extra apparatus being carried by it to be reciprocated, such as is present in the McMahon patent 30 above referred to. Furthermore, by the use of the sleeve 22, which is applied to the piston rod, the threads capable of being used can be much larger, affording a greater bearing surface on the head 19 and may also be of a 35 greater pitch. In addition to this, the tight fit which occurs between the end of the sleeve 22 and the sleeve 14 and the head 16 prevents any escape of fluid which might enter between the heads and the packing 25. It will 40 be understood that if fluid should escape between the heads and enter within the sleeve 14 about the piston rod, it is very apt to squirt out between the collar 11 and the jam nut 15, which is undesirable. The leakage which 45 might occur between the sleeve 22 and the head 19 is effectively stopped, and such leakage which does occur is only limited to that quantity which is necessary to fill the closed hub 24.

50 This is an important feature of this invention for the reason that pistons of this type are frequently used in mud pumps, pumping fluids containing grit, sand and the like. As the fluid is pumped under a high pressure, 55 the sand or grit in the fluid, which leaks, very quickly cuts away the metallic parts about the crevice or opening through which the leakage occurs.

60 The purpose of providing the projections 60 on the interior surface of the packing 25 is as follows: When the piston is assembled in the pump cylinder, the head 19 is the last part to be applied. This is applied upon the sleeve 22 and is rotated by applying a wrench 65 or the like to the hexagonal portion of the

end of the hub 24. In screwing this head upon the sleeve 22 the end faces of the fingers 18 might abut the end faces of the fingers 17, so that the fingers 18 will not enter between the fingers 17, but will merely rotate the head 16 and the sleeve 14. By the use of the projections 26, which are projecting very slightly, one set of projections is caused to fit between the fingers 17 so that rotation of the packing 25 relatively to the head 16, while the head 19 is being applied, is effectively stopped. On screwing up the head 19, if the ends of the fingers 18 should encounter the side faces of the projections 26, the head 19 can be rotated, causing the fingers 18 to ride over these projections and fit against the interior surface of the packing 25 between them. In this way the packing 25 will become locked to some extent against rotation relatively to the head 19, and as it is also effectively locked against rotation relatively to the head 16, the head 16 will be caused to rotate with the head 19 while the head 19 is being screwed up, and in this manner the fingers 18 will be maintained in that position in which they can enter between the fingers 17 on the application of the head 19.

65 From the above described construction it will be readily appreciated that the improved plunger is of simple construction and operation during adjustment. Furthermore, leakage between the heads, which is quite disadvantageous, is effectively prevented by means of the closed hub or cap 24 and the tight fit established between the sleeve 22 and the head 16 and sleeve 14.

70 It will be understood that various changes in the detail of construction may be made without departing from the spirit or scope of the invention as defined by the appended claims.

75 I claim:

1. In a pump, a plunger rod held against rotation upon the plunger rod coupling, a sleeve disposed about the plunger rod, a head mounted upon the sleeve, a threaded sleeve mounted upon the end of the plunger rod, a second head threaded onto the second sleeve, means for holding said heads against relative rotation, and an expansible packing disposed between the heads whereby upon rotation of the first sleeve, said heads may be rotated thereby, causing the second head to move relatively to the first head and thus expand the packing.

80 2. In a pump having a plunger rod coupling, a plunger rod secured against rotation relatively thereto, a sleeve disposed about the plunger rod having one end bearing against the plunger rod coupling, a jam nut threaded onto the mentioned end of the sleeve, a head rigidly mounted upon the other end of the sleeve, a threaded sleeve mounted upon the end of the plunger rod, a second head threaded onto the threaded sleeve, means for

- holding the heads against relative rotation, a packing disposed between the heads adapted to be expanded upon rotation of the first sleeve, causing the heads to be rotated and causing the second head to move toward the first head upon rotation of the first sleeve, said threaded sleeve providing an abutment against which the end of the first sleeve is adapted to abut on tightening the jam nut against the plunger rod coupling.
5. A pump plunger comprising a plunger rod, a sleeve disposed about the plunger rod, a head mounted upon the sleeve, a threaded sleeve mounted upon the plunger rod, a second head threaded onto the threaded sleeve, means for locking said heads against relative rotation, and a packing disposed between the heads, said threaded sleeve providing an abutment against which the first sleeve abuts.
10. 3. A pump plunger comprising a plunger rod, a sleeve disposed about the plunger rod, a head mounted upon the sleeve, a threaded sleeve mounted upon the plunger rod, a second head threaded onto the threaded sleeve, means for locking said heads against relative rotation, and a packing disposed between the heads, said threaded sleeve providing an abutment against which the first sleeve abuts.
15. 4. An expansible packing adapted to be used upon plungers of the class described comprising an annular packing body having staggered projections on its interior surface to be used as and for the purpose described.
20. 5. A pump plunger comprising a piston rod, a sleeve disposed about the piston rod, a head secured to the sleeve, a second head threadedly mounted upon the plunger rod having a closed hub enclosing the end of the plunger rod, means for locking said heads against relative rotation, and means providing abutments upon the plunger rod adapted to limit endwise movement of the first head and sleeve whereby upon rotation of the first head and sleeve, the second head may be adjusted toward or away from the first head, said abutments being adapted to form a liquid tight seal in limiting the movement of the first head and sleeve to prevent leakage of
25. 35. fluid from between the heads through the first head about the plunger rod.
40. 45. In testimony whereof I have signed my name to this specification.
- ERWIN E. MILLER.
